Attorney

UNITED STATES PATENT OFFICE.

WILLIAM H. DANIEL, OF SPOKANE, WASHINGTON.

TOY AEROPLANE.

Application filed June 18, 1927. Serial No. 199,829.

The present invention relates to improvements in toy aeroplanes of the type utilizing rubber bands for the propelling power, and the toy constructed according to my invention is designed for a flight of sufficient distance to insure the novelty and attractiveness of the toy. Means are provided whereby the toy device may be propelled, as a vehicle, along the floor or other hard surface, and in addition floats may be attached and substituted for the wheels of the vehicle to propel the toy on the surface of water, or runners may be used on the toy for propelling it over the surface of snow or ice.

In the adaptation of the toy as a wheeled vehicle for traveling along the floor, the propulsion may be secured by rotating an air propeller, and in addition the front supporting wheels of the toy-vehicle may be driven as an auxiliary means to the propeller. The invention consists in certain novel combinations and arrangements of parts as will hereinafter be more fully pointed out and claimed. In the accompanying drawings I have illustrated one complete example of the physical embodiment of my invention wherein I have illustrated also wheel substitutes that may alternately be used with the toy, in which the parts are combined and arranged according to one mode I have thus far devised for the practical application of the principles of my invention.

Figure 1 is a top plan view of the toy of my invention equipped as a wheeled-vehicle.

Figure 2 is a view in side elevation of the toy of Figure 1.

Figure 3 is a sectional view at line 3—3 of Figure 2.

Figure 4 is a sectional view at line 4—4 of Figure 2.

Figure 5 is a detail view of a float used as a wheel substitute at the front of the toy and Figure 6 is a view of a float used as a wheel substitute at the rear of the toy, these floats being employed when the toy is used on the surface of water.

Figures 7 and 8 are side views of the front and rear runners used as wheel substitutes when the toy is used on a snow or ice surface.

In carrying out my invention I use a body or board 1 at the front end of which is the air propeller 2 fixed to revolve with the propeller shaft 3 that is provided with a fly or balance wheel 4 and the shaft is journaled

in bearings in the walls of a gear box 5 secured at the front of the board and on its top surface, the shaft of course being located in the longitudinal center of the board and extending longitudinally thereof.

Within the box 5 the propeller shaft is provided with a pinion 6 with which a pair of gears 7 and 8 mesh, the gears being fixed to revolve with the spaced, longitudinally extending driven shafts 9 and 10 located parallel with and at the sides of the propeller shaft 3 and journaled also in the walls of the gear housing, or box 5. This train of gears extends transversely of the body of the toy and forms the propelling or propulsion mechanism for the propeller, and the train of gears may be retained against operation, by means of a pawl 11 pivoted at 12 and provided with a counterweight or handle 12, as for instance when the power is being developed by twisting or winding two rubber bands 14 and 15 that are suspended at opposite sides of the longitudinal center of the body of the toy. These endless elastic bands, at their front ends are suspended by hooks 16 from the rear ends of the driven shafts 9 and 10, and at their rear ends are suspended from hooks 17 on the front ends of a pair of power shafts 18 and 19. The power shafts are disposed at the sides of the longitudinal center of the toy and journaled in bearings in the walls of the rear gear casing 20, and of course the power shafts are aligned with their complementary driven shafts at the front of the toy. On the power shafts are pinions 21 and 22 and between these pinions is located the large gear wheel 23 on the power shaft or crank shaft 24 which is also journaled in bearings in the wall of the rear gear housing and provided at its rear end with a projecting hand crank 25. The power gear is provided with a pivoted dog or detent 26 which is shown in locked position in Figure 4 to prevent movement of the power shafts and crank shaft, as during the time the toy is being operated. To develop power, the dog 26 is released, and the pawl 11 is locked with gear 8 as shown in Figure 3 in order that by turning the crank 25 the two rubber bands may be twisted and thus store power in them. After the power has been developed, the dog 26 is set as in Figure 4, and if the toy is to be propelled, the pawl 11 is released, whereupon the untwisting or turning movement of

the rubber bands operates the driving shafts and gears to rotate the propeller shaft and the air propeller.

In addition to the use of the air propeller, a pair of traction wheels 33 may be used to propel the toy across the floor, through the employment of a pulley 27 on the propeller shaft, a belt 28 passing around a pulley 30 and the axle 31 on which the pulley and traction wheels 33 are fixed. The belt passes through a hole 29 in the board 1 and transmits power from the propeller shaft to the axle, and thence to the traction wheels 33, whose tractive power assist in the propulsion of the toy over the floor or ground surface. The front axle is journaled in an under frame or wheel frame 32 of U-shape that is secured at the under side of the board and a pair of diagonal braces 34 are connected at their lower ends to a cross rod 34' fixed in the U-frame, while the upper ends of these braces pass through holes in the board and are threaded to accommodate lock nuts 35. The lock nuts are turned tight against the top surface of the board and hold the braces securely to insure a rigid wheel frame at the front of the toy for the wheels 33.

At the rear of the toy a single steering wheel 36 is used and this wheel may be adjusted by turning on its vertical axis to steering position so that the toy will be propelled in a circle. A wheel bracket 37 is provided in which the steering wheel is journaled and this bracket has a bolt 38 that passes through a hole in the board to accommodate the wing nut 39, and the latter is used to clamp the bracket in adjusted position to properly locate the steering wheel.

In Figure 5 a substitute for the front wheels is shown as a float 40 supported by the float-frame 41 from the wheel frame 32, and in Figure 6 the float 42 and frame 43 are used

as wheel substitutes for the wheel 36 and bracket 37, when the toy is used as a water craft and propelled by the air propeller 2.

In Figure 7 one or more runners 45 are attached at 46 to the wheel frame 32, and in Figure 8 one or more runners 47 are attached by frames 48 and bolts 44 at the rear of the toy as wheel substitutes, thus adapting the toy for use on ice or snow over which it is propelled by the air propeller.

These wheel substitutes form parts of the toy and are readily interchangeable with the wheels and with each other and add interest and mechanical novelty to the construction and operation of the toy.

Having thus fully described my invention, what I claim as new and desire to secure by Letters Patent is—

1. The combination in a wheeled toy with a propeller shaft having a pinion thereon, a pair of spaced driving shafts and driving gears for the pinion, of a crank shaft having a gear thereon, a pair of power shafts having pinions meshing with the gear, and a pair of endless rubber bands suspended between the respective driving and power shafts.

2. The combination in a wheeled toy with a propeller shaft having a pinion and a pivoted pawl for engagement therewith, a pair of spaced driving shafts, and driving gears on the latter shafts meshing with the pinion, of a pair of traction wheels and their axle, power transmission means between the propeller shaft and axle, a crank shaft and gear thereon at the rear of the toy, a pair of power shafts having pinions engaging said gear, and a pair of endless rubber bands suspended between the respective driving and power shafts, and a pivoted detent for co-action with the crank gear.

In testimony whereof I affix my signature.

WILLIAM H. DANIEL.
